UNITED STATES PATENT OFFICE

2,523,064

TIP ASSEMBLY FOR PARACHUTE PROJECTILES

Alfred L. Ruthven, Denver, Colo., assignor of three-fifths to himself as trustee for Betty R. Ruthven, Thomas D. Ruthven, and Sharon A. Ruthven; one-fifth to Helen D. Ruthven, and one-fifth to Louis R. Ruthven

Application January 15, 1946, Serial No. 641,198

5 Claims. (Cl. 46—86)

1

This invention relates to improvements in projectile parachutes of the general type disclosed in my copending application Serial No. 474,240 filed February 1, 1943, and now matured into Patent No. 2,435,367.

Objects of this invention are to provide, in and for projectiles adapted to carry parachutes into the air, (a) improved tip structure; (b) improved parachute engaging and releasing means; (c) a tip, including parachute engaging and releasing means, adapted to be readily engaged to and/or disengaged from the tip end of the projectile; (d) parachute engaging and releasing means of improved structure and operation whereby to accomplish better balancing and direction of the projectile in flight and to increase the length of projected flight.

With these and other objects in view, all of which will more fully hereinafter appear, the invention comprises certain novel constructions, combinations and arrangements of parts as will now be described and defined in the appended claims and as illustrated in the accompanying drawing, illustrative of preferred embodiments of the invention, and in which

Fig. 1 is a side elevation of a projectile, including the present improvement, carrying a parachute and ready for flight.

Fig. 2 is a fragment of Fig. 1, illustrating more exactly the arrangement of the parachute on the tip for most effective operation.

Fig. 3 is an elevation of the projectile and parachute, illustrated at Fig. 1, but illustrating the changes in position of the various parts during reversal of direction between projected flight and opening of the parachute in downward flight.

Fig. 4 is an elevation of the parachute and suspended projectile in downward flight.

Fig. 5 is an elevation of the improved tip assembly taken at right angles to the view thereof in Fig. 1 and without the parachute shown at Fig. 1.

Fig. 6 is a view, partly in elevation and partly in section, of the improved tip assembly, the projectile-engaging tip being shown in section.

Fig. 7 is a view of the butt end of the projectile, on an enlarged scale.

Fig. 8 is a side elevation of another embodiment of the improved tip and parachute engaging fin, showing the same in position as it would be when the projectile is in the position shown at Fig. 3.

Fig. 9 is a view of the embodiment shown at Fig. 8 but in upright position and showing the tip in central, longitudinal section.

Fig. 10 is a view of the embodiment illustrated at Fig. 8 but with the tip upright as in Fig. 9

and taken at right angles to the position illustrated at Fig. 9.

Fig. 11 is a view like Fig. 9 but illustrating another form of parachute engaging fin.

5 The projectile here illustrated is in the form of an arrow adapted to be shot from a bow and the description will be in terms appropriate thereto but, so far as concerns the present invention, any suitable projection device may be used and 10 the projectile may be adapted thereto in form and structure, the present invention residing in the tip for the projectile and in the parachute-engaging fin associated with the tip.

The projectile comprises a shaft 21 provided 15 with suitable feathers or guide fins 22 near its butt end which end is cross notched as illustrated at Fig. 7 for the purpose later described. The forward end of the projectile is plain and adapted to receive thereover the hollow tip 23, 20 of suitable material such as aluminum.

The improved tip 23 has a seat 23a into which the forward end of the projectile may be fitted so that the tip will be carried by the projectile as a part thereof and will form a heavy point or 25 tip on the projectile.

The other end of the tip is bifurcated as at 23b and a parachute-engaging fin 24 is pivoted, as at 25, between the furcations whereby the fin may move to and between the parachute-engaging horizontal position shown at Figs. 1, 2, 5 and 6 and the release position shown at Figs. 3 and 4.

30 A spring 26 encircling the tip and, at one end, hooked thereto as at 27, is engaged to the fin 24 by suitable means as by hooking the free end of the spring into one of the holes 28, said holes being so positioned in the fin that the hooking of the spring into one hole will result in exerting a greater pull upon the fin than if the spring were hooked into the other hole. As many holes 28 as desired may be provided so as to afford a variety 35 of tensions on the fin. Normally spring 26 will draw fin 24 to and hold it in release position as shown at Figs. 3 and 4.

Fin 24 has an upper edge which extends to a 40 substantial distance in both directions beyond tip 23 when the fin is in parachute-engaged position. Referring to the fin as in such position, the upper edge of the fin is substantially horizontal but it is preferably divided into two sections 24a, on a higher level, and 24b on a relatively lower level, a stop 24c being provided at the outer end of portion 24a of the upper edge. Stop 24d is also provided in the lower edge of the fin 24 whereby to contact the tip 23 and limit the 45 swinging of the fin to a point, as shown at Fig. 6,

at which point the edge 24a inclines slightly downwardly to the right, as viewed at Fig. 6.

The parachute, in connection with which this invention is designed to be used, is designated as 29 with shroud lines 30 and shroud-line cord 31 and a crown cord 32.

In operation cord 31 is suitably secured to shaft 21 as indicated at 33 and the parachute is folded over edge 24a in the manner clearly illustrated at Fig. 2, and crown cord 32 is drawn taut and placed in one of the notches in the base of the projectile as clearly illustrated at Fig. 7, the bow string 34, positioned in the other notch, serving to grip cord 32 and hold it taut until projected from the bow.

The pull of the parachute on edge 24a holds fin 24 in the position indicated at Figs. 1, 2 and 6 until the pressure of bow string 34 on crown cord 32 is released by projection. Thereupon the air resistance on the folded parachute serves to hold fin 24 in that same position until the projection force is spent and the projectile begins its curved course from projected flight to dropping flight. As soon as the air resistance substantially lessens, spring 26 draws fin 24 to release position, as illustrated at Fig. 3, and the air resistance slides the parachute off of fin 24 whereupon the parachute opens and floats the projectile to earth in the manner illustrated at Fig. 4.

In the embodiment illustrated at Figs. 8, 9 and 10 I provide a somewhat different fin 34 having a parachute-engaging edge 34a positioned directly above and extending substantially equidistant on each side of tip 23 and terminating in one direction at stop 34b while in the other direction it merges into inclined edge 34c, the fin being rigidly secured between furcations 23b as by pin 35, seating edge 36 and abutting edge 37.

In operation, with this embodiment, the parachute is drawn taut over edge 34a and held taut by crown cord 32 beneath the bow string in the same manner as above described but in this case the parachute is preferably evenly distributed along edge 34a so that it will be substantially "centered" with or evenly balanced upon the projectile. The parachute will be held against this edge in projected flight by air resistance in the manner above described.

When the projecting force is spent and the projectile is following the arc from projected flight to dropping flight, the air resistance acting against the extension portion of the fin beneath edge 34c, will rotate the projectile until the extension portion of the fin is on the upper side of the projectile as indicated at Fig. 8, in which position, as the projectile begins to move downward, the air resistance will slide the parachute along and off of edge 34a and along and off of edge 34c freeing it to open and float the projectile to earth as above described.

The embodiment illustrated at Fig. 11 will operate on a like principle. Here the fin 38 has a plain top edge 38a and is secured to the tip in substantially the same manner as the fin last above described having a pin 35, seating edge 36 and abutting edge 37, the same as previously described. This fin may also conveniently have another abutting edge 39. The larger area of the fin is to the left of the tip as viewed at Fig. 11. The parachute is folded over the edge 38a in the same manner as over edge 34a in the last previous described embodiment and is preferably distributed centrally as regards tip 23 so that the air resistance upon the parachute during pro-

jected flight will be equal on each side of the tip. The more extensive portion of the fin will be on the upper side of the projectile as it starts its downward flight, as (and for the same reason as) last above described, whereupon the air resistance will slide the parachute along and off the then upper end of edge 38a, freeing it to open and float the projectile to earth.

When a parachute of exceedingly light material is used the simple embodiment illustrated at Fig. 11 will be found quite satisfactory for ordinary use and the embodiment illustrated at Figs. 8 to 10 will be found entirely satisfactory. With heavier materials the preferred embodiment first described will be found the best and that embodiment will operate with the lightest of materials at least as well as, and sometimes better than, either of the other embodiments.

I have illustrated in the drawing and herein described many details of construction but it will be understood that other equivalent structures may be used in many cases which equivalents will occur to those skilled in the art and I do not wish to be limited in protection to the details illustrated and described but I desire patent protection including equivalent or alternative structures within the spirit and scope of the foregoing specification and a broad reading of the appended claims.

I claim:

1. A projectile adapted to carry a folded parachute having a crown cord and a shroud-line cord, comprising a shaft carrying at its forward end a flat fin extending outwardly from said shaft in both directions but having a larger area on one side of the shaft than on the other side thereof, and having a front edge substantially perpendicular to the axis of the shaft and adapted for the folding of a parachute thereover.

2. In combination with a shaft and a parachute attached thereto, a member carried at the tip of the shaft adapted to receive a parachute folder thereover, means for holding said parachute taut upon said member in such folded position, said holding means being releasable automatically responsive to the projection of the shaft, said member being so positioned that the parachute will be held upon said member responsive to air resistance during projected flight, said member being flat and extending in both directions from the axis of the shaft but having a larger area on one side of the shaft than on the other side thereof.

3. A parachute projecting and releasing device comprising, in combination, a shaft, a parachute attached thereto, a thin, flat member carried at the tip of the shaft having a front edge substantially perpendicular to the axis of the shaft and adapted to receive said parachute collapsed and folded thereover, said member extending from the shaft laterally in both directions but having a larger area on one side of said shaft than on the other side thereof.

4. A tip assembly for parachute-carrying projectiles, comprising a tip member having a seat therein for the front end of the projectile and a fin carried by the tip member and extending outwardly from said member in opposite directions and having a front edge substantially perpendicular to the longitudinal axis of the projectile and adapted for folding the parachute thereover, said fin having a greater area on one side of said tip member than on the other side and

the said edge terminating in a stop element on the side having the lesser area.

5. A tip assembly for parachute-carrying projectiles, comprising a tip member having a seat therein for the front end of the projectile and a fin carried by the tip member and extending outwardly from said member in opposite directions and having a front edge substantially perpendicular to the longitudinal axis of the projectile and adapted for the folding of a parachute thereover, said fin being pivoted in said tip member whereby to swing in a plane including the longitudinal axis of the tip member and resilient means connecting the tip member and the portion of the fin at one side of the tip member whereby to normally swing said fin to incline its said edge away from the said perpendicular position and toward alignment with the longitudinal axis of the projectile.
